UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO, A CORPORATION OF OHIO.

WEAR-PLATE FOR JOURNAL-BOXES.

1,230,859.

Specification of Letters Patent. Patented June 26, 1917.

Application filed December 24, 1914. Serial No. 878,858.

To all whom it may concern:

Be it known that I, ALBERT O. BUCKIUS, Jr., a citizen of the United States, residing at Chicago, in the county of Cook and State of Illinois, have invented new and useful Improvements in Wear-Plates for Journal-Boxes, of which the following is a specification, reference being had to the accompanying drawings, in which—

Figure 1 is a perspective of a journal box, showing wear plates in the pedestal guides thereof; Fig. 2 shows details of wear plates intended to be inserted in complementary guides on one side of the journal box; Fig. 3 shows a perspective of a pedestal having wear plates positioned thereon, and Fig. 4 is a detail of the pedestal wear plate.

My invention relates to wear plates for journal boxes and journal box pedestals, and consists in providing a wear plate which may be attached either to a journal box or to a journal box pedestal, and which completely protects one from wear by the other. My invention also consists in the construction and coöperation of the parts which I shall hereinafter describe and claim.

Referring to the drawings, the reference letter A indicates a journal box, B the pedestal and C, C' the wear plates. The journal box is provided upon its sides with vertical, parallel ribs 2 which form grooves or guides for reception of the truck pedestals. The wear plate C is of channel shape, having a web 3 and flanges 4 at right angles thereto, which bear against the inner faces of the ribs 2, and right angled projections 5, parallel with the web 3, which bear against the outer faces of the ribs 2. The wear plate C also has extensions 6 at its top and bottom, which bear against the top and bottom of the ribs 2 and also against the transverse faces 7 on the box.

The wear plate C may be welded or riveted to the part it is intended to protect. I preferably secure the wear plate to the part by spot welding, and I have found that, if welded at the portions indicated in shaded lines marked a, a sufficient adhesion to the part is secured.

It has been found that where inserts of the form shown in the Case Patent No. 1,063,655, dated June 3, 1913, are used, such inserts become worn, particularly at the bottom, sometimes wearing clear away at this point and wearing very little at the

top. Such wear will of course render the box unfit for service and it must be scrapped, although the box itself, except at this particular point, has not become worn to an appreciable extent. When boxes are equipped with wear plates in accordance with my invention and the wear plate becomes worn away by the friction of the pedestal, the wear plate can easily be removed with a chisel, without in any way injuring the box, and a new wear plate riveted or welded to the box in the manner above described.

It is obvious that the saving thus occasioned is considerable, since journal boxes can be used for a much longer period than has been possible heretofore. A further advantage in the use of the wear plate of my invention is that the armored or protected area is greatly increased, since the whole area of the pedestal guide in the journal box is completely protected by the wear plate and there can be no wear of the journal box at its points of contact with the pedestal. I have also found that the material comprising the wear plate can be made of any desired hardness, and since it is preferably applied after the box has been annealed, it does not have to be of a character to resist annealing. The wear plates of my invention may be applied to boxes either of gray or malleable iron, or cast steel.

In Figs. 3 and 4 I have shown my invention as applied to the portions of the pedestal B which seat in the pedestal guides of the journal box. The faces and sides of the pedestal columns 8, which fit into the pedestal guides on the journal box, are protected by the webs 3' and flanges 4' of the wear plates C', and the wear plates C' may be secured to the pedestal columns 8 by riveting or welding, or by spot welding as is indicated at a'.

In carrying out my invention either the pedestal guides on the journal box or the pedestal, or both, may be protected by the wear plates which I have described.

It is obvious that various modifications may be made in the constructions which I have shown and described, without departing from my invention.

What I claim is:

1. A journal box having pedestal guides in its sides, in combination with a pedestal having projections adapted to seat in guides of the journal box, and a wear plate of

105

110

channel shape welded to one of said parts but detachable therefrom.

2. A wear plate for castings, comprising a piece of metal having a web, and flanges at right angles to the web, each flange having a laterally-extending projection at an angle thereto and parallel with the web.

3. A casting having a groove, a metal wear plate secured in said groove to form 10 a lining therefor, said plate consisting of a web, extensions at the top and bottom of said web at an angle thereto and flanges at the sides of said web at an angle thereto, each of said flanges having a laterally-extending projection, said web, extensions, 15

flanges and projections bearing against the said casting and forming a protection therefor, in combination with means for securing the said wear plate to the said casting.

4. A wear plate for castings, comprising 20 a piece of metal of channel shape provided upon its ends with extensions at right angles to the web and flanges of said channel, said extensions projecting over the body of the casting and away from the space inclosed 25 by said web and flanges.

ALBERT O. BUCKIUS, JR.
